(57) **CLAIM**

The ornamental design for a carrier pigeon matching cage, as shown and described.

DESCRIPTION

FIG. 1 is a perspective view of a carrier pigeon matching cage showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a perspective view thereof, showing the carrier pigeon matching cage in an open state of use, with the door on the right side removed; and,

FIG. 9 is another perspective view thereof, showing the carrier pigeon matching cage in an open state of use, with the door on the right side open, and the bottom drawers on the left and right open.

The broken lines in the figures illustrate portions of the carrier pigeon matching cage that form no part of the claimed design.

Any shading is not a feature of the design but is utilized to illustrate the surface contours of the carrier pigeon matching cage design in the drawings.
